UNITED STATES PATENT OFFICE.

GEORGE W. COPE AND WILLIAM L. BERTRAM, OF DETROIT, MICHIGAN;
ASSIGNORS TO FRANK A. NIEBERDING, OF SAME PLACE.

DESIGN FOR A STOVE.

SPECIFICATION forming part of Design No. 32,041, dated December 26, 1899.

Application filed December 1, 1899. Serial No. 738,923. Term of patent 7 years.

To all whom it may concern:

Be it known that we, GEORGE W. COPE and WILLIAM L. BERTRAM, citizens of the United States, residing at Detroit, in the county of Wayne and State of Michigan; have invented a new and original Design for a Stove, of which the following is a specification; reference being had therein to the accompanying drawings, in which—

10 Figure 1 is a perspective view, and Fig. 2 is a side elevation.

A is the base-section, which is substantially rectangular in form, with rounded corners, and having a bulging front *a* and the enlargement or ring *b* at its lower end.

15 B is a cylindroidal upper section rising from the base-section and having a ledge *c* thereon.

C is a cap surmounting the section B, and 20 D are curved bars rising from the ledge *c* at

the front corners of the base-section and extending upwardly to the cap-section.

E is a scroll ornament rising from the ledge *c* centrally in front of the section B.

The leading feature of the design is the substantially rectangular base-section having the bulging front, together with the cylindroidal upper section rising from said base, and having the surrounding ledge on the top of the base. 25

What we claim as our invention is—

The design for a stove substantially as herein shown and described.

In testimony whereof we affix our signatures in presence of two witnesses.

GEORGE W. COPE.

WILLIAM L. BERTRAM.
